Attorney

UNITED STATES PATENT OFFICE.

GEORGE F. BANTA, OF CLEARFIELD, PENNSYLVANIA, ASSIGNOR OF ONE-HALF TO LEN A. BANTA AND ONE-HALF TO FREDERICK B. KERR, BOTH OF CLEARFIELD, PENNSYLVANIA.

DOOR CLOSURE.

Application filed May 11, 1927. Serial No. 190,621.

This invention relates to an improvement in door closures.

The object of the invention is to provide a double-seal for close fitting doors and other similar forms of closures, as for instance as used on refrigerators, ice boxes, refrigerator cars and, in fact, wherever a closure is desired to closely confine air, gas or a liquid, or to provide a good insulator 10 for a cooling space.

A further object of the invention is to allow for cleaning both opposite sides of plates of glass which are mounted in refrigerator or other similar doors where several 15 thicknesses of glass are used. It has been customary in the art to provide display refrigerator doors with several thicknesses of glass in an effort to secure a better insulating door and it has not been possible heretofore 20 to clean the inside surfaces of the glass by reason of the construction of the door, but this is accomplished by the use of this invention.

The door is formed of two or more sections 25 which are preferably independent of each other and kept in spaced apart relation by means of suitable resilient means as for instance coil springs sleeved over bolts which extend between the two sections of the door 30 and hold the sections apart while the bolts limit the outward movement of the two sections relative to each other. Each of the sections carries a glass and by reason of the independence of the two sections, it is possible 35 to clean both sides of the glass in each section. The springs between the two sections likewise allow for a double-seal between the door and the door-frame, one of the seals being carried by the main pivoted door 40 section while the other is resiliently carried by the movable section. In this way, a tight fit and closely confining door is obtained.

In the accompanying drawings:

Fig. 1 is a perspective view of the door; 45 and

Fig. 2 is a horizontal sectional view therethrough.

The door may be used as a closure for refrigerators, refrigerator cars or, in fact, 50 wherever it is desired to provide a tight fit between the door and the frame-work or articles to which it is applied. As shown in Fig. 2, the frame or wall for supporting the door is designated generally by the numeral 55 1, and has the main door section 2 hinged

thereto as at 3. The main section 2 carries one or more plates of glass 4, there being two shown in the drawings. A second or auxiliary section 5 is held in spaced apart relation from the main section 2 by means of expanding spiral springs 6, which are seated in suitably formed recesses 7 in the door sections 2 and 5. The section 5 likewise carries a plate of glass 8, which cooperates with the plates 4 for the purpose of 60 insulating the door. The springs 6 are sleeved upon bolts 9 which extend between the sections 2 and 5 and serve to connect the sections of the door together and confine the outward movement of the section 5 relative 65 to the section 2.

A cushion seal 10 which may be formed of felt, rubber or any suitable material, is secured about the edge of the main section 2 of the door, as shown in Fig. 1, for engaging the supporting frame for the door or similar closure to provide a tight seal therebetween whenever the door is closed by any suitable form of locking handle (not shown). A corresponding cushion seal 11 is secured about the inner edge of the section 5, as shown in Fig. 1, to engage a ledge 12 formed in the door-frame. The door is shown as closed, in Fig. 2, and when in such closed position it is doubly sealed as at 10 and 11. The spiral springs 6 exert pressure on the seal 11 and hold it tightly against the ledge 12 and together with the seal at 10 it is obvious that a very tight fit is obtained between the door and its supporting frame. 80

As shown in the drawings, the sections 2 and 5 are entirely separate from each other and are held in spaced apart relation by means of the springs 6. The frames of the sections are not joined and in that way it is possible to gain access to both sides of the glasses 4 and 8 in order to clean these glasses and to give the door a better appearance, especially when used for refrigerator display cases. 95

As stated above, the double seal is provided at 10 and 11, the seal at 10 being closed by means of the hinges and locking lever or handle, which forces the main door section 2 against its supporting frame, and the seal at 11 is held tightly against the ledge 12 in the frame by the expanding springs 6, and in this way the door is kept tightly sealed to act as an insulator especially where used on refrigerators or similar articles in order to 110

keep in the cold air and keep out the warm air. The invention may likewise be similarly applied to any suitable form of closure whenever it is desired to closely confine air, 5 gas or liquid.

I claim:

1. A closure of the character described including independent sections having the frames thereof entirely disconnected from each other, means for limiting the outward movement of each section relative to the other, and resilient means interposed between said sections normally tending to hold the sections in spaced apart relation. 10
2. A closure of the character described including independent sections formed of frames disconnected from and independent of each other, each of said frames carrying a glass, bolts extending between the frames for limiting the outward movement thereof relative to each other, and resilient means 15
3. A closure of the character described including independent sections, resilient means normally tending to hold said sections in spaced apart relation, and a cushion seal carried by each of the sections. 20
4. A closure of the character described including independent sections formed of frames disconnected from and independent of each other, each of said frames carrying a glass, bolts extending between the frames for limiting the outward movement thereof 25

relative to each other, resilient means sleeved over the bolts and interposed between the frames of the sections normally tending to hold said sections in spaced apart relation, 40 and a cushion seal carried by the frame of each of the sections in position to tightly fit against a portion of the supporting frame for the door.

5. A closure of the character described including independent sections having the frames thereof entirely disconnected from each other, bolts extending between the sections for limiting the outward movement thereof relative to each other, said bolts being the only connection between the sections, and resilient means sleeved over the bolts and interposed between the frames normally tending to hold the sections in spaced apart relation. 45 50 55

6. A closure of the character described including independent sections having the frames thereof entirely disconnected from each other forming circumferential openings for gaining access to the space between the sections, bolts extending between the frames of the sections for limiting the outward movement thereof relative to each other, said bolts being the only connection between the sections, resilient means sleeved over the bolts and interposed between the frames normally tending to hold the sections in spaced apart relation, and plates of glass mounted in the sections. 60 65

In testimony whereof I affix my signature.

GEORGE F. BANTA.
